UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

SHAFT-HANGER.

1,378,402.

Specification of Letters Patent.

Patented May 17, 1921.

Original application filed February 8, 1917, Serial No. 147,296. Divided and this application filed November 16, 1918. Serial No. 262,760.

To all whom it may concern:

Be it known that I, ALBERT H. DE VOE, a citizen of the United States, residing at Westfield, in the county of Union and State 5 of New Jersey, have invented certain new and useful Improvements in Shaft-Hangers, of which the following is a specification, reference being had therein to the accompanying drawings.

10 This invention relates to a shaft-hanger for power-stands, such as that shown in my application Serial No. 147,296, filed February 8, 1917, upon which Letters Patent No. 1,347,840, issued July 27, 1920, and of 15 which this application is a division.

The objects of the invention are to provide a shaft-hanger which is readily adjustable on a support in a number of ways, and provide a support for the hanger also 20 having several adjustments, whereby a plurality of hangers in a power-stand may be readily and accurately alined.

The hanger comprises a shaft-bearing trunnioned in a supporting yoke, the latter 25 in turn being rotatably and slidably adjustable in a support for the hanger. The support is carried by a base on which it may be rocked in any desired direction and secured in adjusted position.

30 In the accompanying drawings, Figure 1 is a vertical section through the hanger-support, showing its adjustable connection with the base or floor-plate. Fig. 2 is a plan view of the base. Fig. 3 is a transverse section on the line of the seats 14 in Fig. 2. Fig. 4 is a side elevation, partly broken away, showing the manner in which the hanger is secured in its support. Fig. 5 is a central section through the hanger at right 35 angles to the view in Fig. 4. Fig. 6 is a side elevation, showing two adjacent units 40 of a power-stand and their connections.

Referring to the accompanying drawings 1 is a base or floor-plate having a central 45 raised portion and depressed seats 2, the plate being secured to the floor by bolts 3 passing through the depressed seats and lag screws 4 passing through the outer portion of the plate. The raised portion has a 50 central elongated aperture 5 having at one end an enlargement 6, the enlargement being adapted to receive the head of a bolt 7, whose shank may then be slid into the narrow portion of the aperture with its

head in engagement with the lower surface 55 of the plate. Mounted on the base is a hollow column 8 having an apertured cross piece 9 through which the bolt 7 passes, a nut 10 being provided for the threaded upper end of the bolt. Lateral openings 60 11 in the column allow access to the bolt and nut. The lower end of the column is provided with an outwardly flanged portion 12, and adjusting screws 13 passing through said portion are adapted to engage the 65 raised seats 14 provided on the base or floor-plate, as clearly shown in Fig. 3. Lock-nuts 15 are provided for the adjusting screws. A combined power-transmitter and shaft-hanger 16 is carried by the upper end of the 70 column. Referring to Fig. 5 it will be seen that the hanger has a central reduced portion 17 in which a bearing 18 for the shaft 19 is mounted. The portion 17 carries trunnions 20 having recesses which are engaged 75 by center screws 21 mounted in the yoke 22. The yoke 22 has a shank 23 which is rotatably and longitudinally adjustable in the upper end of column 8, a set-screw 24 being used to secure the shank in adjusted position. Shelves 25 carried by the column 8 are adapted to support sewing machines, the latter being belt driven from the power-transmitters. Adjacent power-transmitters are connected by the shaft 19 and also by a 80 T-beam 26 and brace-rods 27 (Fig. 6). A hanger 28 is carried on one of the T-beams, and belting 29 connects the pulley 30 mounted on the shaft 19 in the hanger with a main-shaft not shown. Spool-holders 31 are 85 hung on the rods 27 by means of hooked arms 32. Treadles 33 are mounted adjacent the base of each column, each treadle being connected by suitable operating mechanism with a lever 34 which actuates a clutch in 90 the transmitter in the manner fully shown and described in my application Serial No. 260,254, filed Oct. 30, 1918, upon which Letters Patent No. 1,347,841, issued July 27, 95 1920.

In use a desired number of columns and transmitters are assembled in line, a single power-shaft 19 being used for all. With the construction above described the various shaft-hangers may then be readily adjusted 100 in proper alinement. By loosening the set-screw 24 the hanger may be bodily raised vertically with respect to the column 8 or

rotated in a horizontal path, and by loosening the center screws 21 the hanger may be rotated in a vertical path. The hanger may also be bodily moved from side to side by 5 adjustment of the screws 13, which allows the column 8 to be rocked about its base.

By the use of this column the usual power table is done away with. The power tables ordinarily occupy considerable floor space, 10 and furthermore in passing from a machine on one side of the table to another on the other side it is necessary for an operator to go around the end of the table and come back on the other side with consequent inconvenience and loss of time. Then too in the power tables the main power shaft and pulleys thereon are usually mounted below the top of the table where they occupy considerable space and 15 are down where articles may become entangled therein. The machines are furthermore accessible from one side only. In applicant's arrangement a plurality of machines are mounted around the individual 20 columns which are spaced from each other, and thus they occupy a minimum of floor space and each machine is accessible at all times from different sides. Also the main power shaft and driving pulleys are located 25 above the machines and the heads of the operators, where they are out of the way and where articles are not liable to become entangled therein. Another advantage of applicant's arrangement of machines is that 30 separate units may be readily added without interfering with the units already installed or units may be discontinued and removed without interfering with those retained.

40 Having thus set forth the nature of the invention, what I claim herein is—

1. A sewing machine stand comprising a column provided with a base having fastening means for securing it in position, a 45 shelf secured to said column with means for maintaining in position thereon a sewing machine, and overhead shaft-bearings carried by said column and adapted to receive and sustain a power-shaft for driving the 50 sewing machines.

2. In combination, a sewing machine stand comprising an upright column carrying intermediate its head and foot a sewing machine shelf or table and formed at its upper 55 end with a vertical boss, a power-transmitter frame-support fitted to and secured on said boss for adjustment both axially and circularly, and a transmitter-frame sustained by said support and provided with power-shaft bearings.

3. In combination, a sewing machine stand composed of a plurality of connected units each comprising an upright column carrying intermediate its head and foot a sewing machine shelf or table and sustaining 65

upon its head a power-transmitter frame provided with power-shaft bearings adjustable both vertically and laterally for alignment of said power-shaft bearings with those of the adjacent column or columns.

4. In combination, a sewing machine stand composed of a plurality of connected units each comprising an upright column carrying intermediate its head and foot a sewing machine shelf or table and sustaining upon its head for both lengthwise and circular adjustment upon a vertical axis a power-transmitter frame provided with power-shaft bearings adapted for alignment with those of the adjacent column or 70 columns.

5. In combination, a sewing machine stand comprising an upright column carrying intermediate its head and foot a sewing machine shelf or table and formed at its upper end with a vertical boss, a yoke having a shank fitted to and adjustable both axially and circularly upon said boss and provided with transverse bearing elements, and a power-transmitter frame pivotally mounted 75 upon said bearing elements and provided with power-shaft bearings.

6. In combination, a sewing machine stand comprising an upright column carrying intermediate its head and foot a sewing machine shelf or table and having at its upper end a vertical boss, said column having at its base means for its lateral angular adjustment, a yoke having a shank fitted to and adjustable both axially and circularly upon said boss and provided with transverse bearing elements, and a power-transmitter frame pivotally mounted upon said bearing elements and provided with power-shaft 80 bearings.

7. A sewing machine stand comprising a base member, a support connected thereto and universally adjustable thereon, a bearing member having a drive shaft therein, and a universally adjustable connection between said bearing member and support.

8. A sewing machine stand comprising a base member, a support adjustably connected thereto, a bearing member carried by said support and having a drive shaft therein, 110 and means for adjusting said bearing member longitudinally, transversely and angularly with respect to the axis of said support.

9. A sewing machine stand comprising a base member, a support, means for internally securing said base member and support, means for angularly adjusting said support relatively to said base member, a yoke rotatably and slidably mounted in said support, 120 a bearing member trunnioned in said yoke, and a drive shaft carried by said bearing member.

10. A sewing machine stand comprising a base member, a bearing member having a 130

shaft therein, and a plurality of universally adjustable connections between said members, including means for adjusting the shaft bodily with respect to the base member.

11. In combination, a sewing machine stand composed of a plurality of connected units each comprising an upright column, a machine support carried by each column

intermediate its top and base, machines carried by said supports, bearings carried by the columns above the machine supports, a power-shaft carried thereby, and power-transmitting means connecting the shaft and the machines.

In testimony whereof I have signed my name to this specification.

ALBERT H. DE VOE.
